A CORPORATION OF DELAWARE

CONTROL FOR ELECTRON TUBES

Application filed October 30, 1930. Serial No. 492,220.

This invention relates to the control of certain gaseous electron discharge tubes of the type in which discharge between the anode and cathode is initiated when the potential of the grid with respect to the cathode exceeds a critical positive or negative value. Such tubes are usually provided with a very small anode surface.

In another aspect the invention relates to the use of electron tubes of the above described character in connection with a phase failure and phase reversal protective system such as described in our co-pending application, Serial No. 432,278, filed February 28, 1930.

An object of the invention is to provide means whereby a tube of the above described character will only respond when the grid potential with respect to the cathode is above the critical positive value and will not respond when the voltage is below the critical negative value or vice versa.

Another object is to provide improved means responsive to abnormal operating conditions in a polyphase circuit such as phase failure, phase reversal or unbalance of the voltages, using a tube of the character described heretofore.

Other objects and advantages will herein after appear.

The accompanying drawings illustrate one embodiment of our invention.

Figure 1 shows our invention embodied in a phase failure and phase reversal protective system similar to that generally described and claimed in the above mentioned co-pending application.

Fig. 2 illustrates the relation between plate voltage and grid voltage of the type of tube which forms part of a system embodying the present invention.

Figs. 3 to 8, inclusive, are diagrams of the voltages and currents obtaining in the system under different conditions of power supply.

Referring to Fig. 1 the same diagrammatically illustrates the invention as employed in connection with a three phase power supply system. A, B and C are the terminals of a power supply system in which

the voltages between any two of the three lines are equal. A transformer having a primary winding 1 is connected between the lines A and B. The transformer has a voltage tap in the center of its primary winding 55 and between such tap and the line C are connected in series the two non-inductive resistances 2 and 3. An electron tube 4 of the gaseous type having a cathode 5, an anode 6 and a grid 7 is connected in series with an electro-magnetic relay 8 between the mid tap of the winding 1 and the line B. The transformer is also equipped with a secondary winding 9 which is connected between the point intermediate of the resistances 2 and 3 60 and the grid 7. A rectifier 10 of any well known type having preferably a low impedance has a cathode 12 which is connected to the grid 7 while an anode 11 of said rectifier is connected to the cathode 5. 65

The tube 4 is of a type in which discharge between the anode and cathode is initiated when the potential of the grid with respect to the cathode is either above a certain positive or below a certain negative value. This 70 critical value at which the tube responds varies with different potentials between the anodes and cathodes and depends upon the construction of the tube. 75

Fig. 2 diagrammatically illustrates the relation between the grid potential E_g and the anode potential E_p of the tube such as employed in the present system. The tube conducts current only when the anode is positive with respect to the cathode and for any instantaneous positive value of the voltage E_p the tube will initiate a discharge only if the grid potential E_g with respect to the cathode is above or below the values within the shaded area of the diagram Fig. 2. After 80 the flow of current during the positive half cycle has once been initiated, current will, of course, flow during the remainder of such half cycle and the tube will act in substantially the same manner as all gaseous discharge tubes. 85

In the present system, initiation of current flow during the positive half cycle is controlled by controlling the phase relation between the grid voltage and the plate or anode 90 100

- voltage during the positive half cycle so that under normal conditions the voltage impressed upon the grid has a sufficiently high positive value at the beginning of the positive half cycle to start current flow, while under abnormal conditions the grid voltage is at all times substantially below the positive value which will start current flow during the positive half cycle. However, unless special provision is made, during abnormal conditions, the grid potential during the positive half cycle of the plate voltage might attain a sufficiently low negative value to start current flow through the tube. In order to avoid this, the rectifier 10 is connected between the cathode and the grid of the tube in such a manner that practically no current can flow from the grid to the cathode through the rectifier circuit, while the flow of current in the opposite direction over the same path is substantially unobstructed, so that when the grid potential tends to attain a negative value with respect to the cathode, current flows from the cathode through the rectifier to the grid and maintains the latter at a negative value with respect to the cathode which differs only slightly from zero and thus prevents the initiation of a discharge through the tube.
- 30 The apparatus functions in the following manner:

Assume that the voltages of the power supply system are balanced and that the normal phase rotation of the same is counter-clockwise. By referring to Fig. 3, it will be apparent that the voltage between the anode 6 and the cathode 5 may be represented by the horizontal vector E_p , while the grid voltage E_g has two components, namely, the voltage drop through the resistance 2 which may be represented by the vector E_r and the voltage induced in the secondary winding 9 which may be represented by the vector E_t . If the voltages in the system are assumed to be rotating counter-clockwise as indicated by the arrow, the instantaneous voltages of the tube may be represented as in Fig. 4, where E_p is the instantaneous plate voltage and E_g the instantaneous grid voltage. The dotted lines 50 E_c and E^{1c} show the critical voltages beyond which the voltage of the grid must fall in order to start anode current during the half cycle of positive anode voltage, it being understood that once the current has started 55 during the positive half cycle, it cannot be stopped by any change in the grid voltage.

If the grid voltage, which is represented by the curve E_g , is positive during the beginning of the positive half cycle and its 60 value is above the critical value as represented by Fig. 2, current starts to flow just after the beginning of this half cycle and any subsequent change in the instantaneous grid voltage has no further effect upon the 65 functioning of the tube and hence upon the

amount of energy passing through the translating device 8. This translating device may be, for instance, a relay equipped with contacts for the control of other instrumentalities and the effective current corresponding to E_p and which passes through the relay under normal conditions is sufficient to cause it to close such contacts.

If now the phase rotation of the supply lines is reversed, the voltage relations are modified as illustrated in diagram Fig. 5. Fig. 6 shows the relation of the instantaneous grid and plate voltages and it is apparent that during practically the entire positive half cycle the grid voltage is slightly negative but less than the critical value so that the tube becomes conducting only during the very last fraction of this half cycle or not at all with the result that the effective current which passes through the relay 8 is reduced to a sufficiently small value to cause it to open its contacts and thus cause the connected controlling instrumentalities to respond.

Fig. 7 represents the relation of the voltages when a short circuit exists between the lines C and B, while

Fig. 8 is a diagram for the case where a short circuit takes place between the lines C and A. In both cases the instantaneous grid voltage is negative during the positive half cycle but on account of the inter-position of the rectifier 10 between the cathode and the grid this grid voltage is of such a small value as to prevent the initiation of discharge between the main electrodes and thus the relay receives no current.

It will be obvious that the system illustrated in Fig. 1 may also be applied to a power supply having a different number of phases than that shown and it will further be apparent that the rectifier 10 may be employed in connection with a gaseous discharge tube of the character described for other purposes where it is desired to reduce the negative grid voltage which would otherwise obtain without said rectifier.

It will further be clear that the connections of the rectifier may be reversed so that the negative grid voltage which is normally impressed upon the tube is not materially modified thereby whereas the positive grid voltage during the other half cycle is reduced to a value which departs only slightly from zero and thus is incapable of initiating discharge through the tube.

What we claim as new and desire to secure by Letters Patent is:

1. The combination with a gaseous discharge tube having an element which, when subjected to a voltage above a critical positive or below a critical negative value, initiates discharge between the main electrodes of said tube when the latter have impressed thereon a suitable potential difference, of a

unilaterally conducting device associated with said element and one of the main electrodes of said tube to prevent the potential impressed on said element attaining one such critical value, whereby initiation of discharge of said tube is rendered dependent upon the control voltage attaining the other critical value.

2. The combination with a gaseous discharge tube having a grid which initiates discharge between the main electrodes of said tube when said grid is subjected to a voltage above a critical positive or below a critical negative value and a suitable potential difference is impressed upon said main electrodes, of a rectifier connected between said grid and one of the main electrodes of said tube to prevent the potential impressed on said grid attaining one such critical value, whereby initiation of discharge of said tube is rendered dependent upon the control voltage attaining the other critical value.

3. The combination of a current supply, a translating device, a gaseous discharge tube in circuit with said supply and said translating device and having a grid which initiates discharge between the main electrodes of said tube when said grid is subjected to a voltage above a critical positive or below a critical negative value and a rectifier connected between said grid and one of the main electrodes of said tube to prevent the potential impressed on said grid attaining one of said critical values, whereby initiation of discharge of said tube is rendered dependent upon the control voltage attaining the other critical value.

4. The combination of a current supply, a translating device, a gaseous discharge tube in circuit with said supply and said translating device and having a grid which initiates discharge between the main electrodes of said tube when said grid is subjected to a voltage above a critical positive or below a critical negative value, means for impressing upon said grid a control voltage responsive to a condition of power supply and a rectifier connected between said grid and one of the main electrodes of said tube to prevent the potential impressed on said grid attaining one of said critical values, whereby initiation of discharge of said tube is rendered dependent upon the control voltage attaining the other critical value.

5. The combination of an alternating current supply, a translating device, a unilaterally conducting gaseous discharge tube in circuit with said supply and said translating device and having a grid which initiates discharge between the main electrodes of said tube during positive half cycles of said supply when said grid is subjected to a voltage above a critical positive or below a critical negative value, means for impressing

upon said grid a control voltage responsive to

a condition of power supply, and a rectifier connected between said grid and one of the main electrodes of said tube to prevent the potential impressed on said grid attaining one of said critical values, whereby initiation of discharge of said tube is rendered dependent upon the control voltage attaining the other critical value.

6. In combination a polyphase current system, a gaseous electron tube connected to said system and having a grid which initiates discharge between the main electrodes of said tube during positive half cycles of said supply when said grid is subjected to a voltage above a critical positive or below a critical negative value, means to normally impress upon the grid a voltage which lags a given angle with respect to the anode voltage so as to insure starting of the discharge current through said tube substantially at the beginning of the positive half cycle of the impressed voltage and to reduce said lag to thereby stop said discharge, and a rectifier connected between said grid and one of the main electrodes of the tube to prevent the potential impressed upon said grid attaining one of said critical values whereby initiation of discharge of said tube is rendered dependent upon the control voltage attaining the other critical value.

7. In combination a polyphase circuit, a load circuit, a vapor electric device provided with a cathode and an anode connected between certain phases of said polyphase and said load circuit and a grid also connected to said polyphase circuit and arranged to control the current transmitted between said cathode and anode, said grid being capable of initiating discharge between the main electrodes of said tube when subjected to a voltage above a critical positive or below a critical negative value, such connection being adapted to normally impress upon said electrode a voltage which lags a given angle behind the voltage of the alternating current circuit so as to insure starting of the current between said cathode and anode at the beginning of the positive half cycle of the voltage of the alternating current circuit and to reduce the lag of said control voltage to thereby prevent such starting, and a rectifier connected between said grid and one of the main electrodes of said tube to prevent the potential impressed upon said grid attaining one of said critical values whereby initiation of discharge of said tube is rendered dependent upon the control voltage attaining the other critical value.

8. In combination a polyphase circuit, a translating device, a vapor electric device provided with a cathode and an anode connected in series with said translating device to said circuit so as to receive space current therefrom, said vapor device being provided

with a grid arranged to initiate discharge between the main electrodes of said tube during positive half cycles of said tube when said grid is subjected to a voltage above a critical positive or below a critical negative value, said electrode being connected to the circuit so as to be normally subjected to a potential which lags a given angle behind the cathode potential, such lag being reduced by abnormal current and voltage conditions in the circuit, and a rectifier connected between said grid and one of the main electrodes of the tube to prevent the potential impressed on said grid attaining one of said critical values whereby initiation of discharge of said tube is rendered dependent upon the control voltage attaining the other critical value.

In witness whereof, we have hereunto subscribed our names.
